LUBRICATING MECHANISM FOR SEWING MACHINES

Original Filed June 28, 1921 7 Sheets-Sheet 7

UNITED STATES PATENT OFFICE.

JOHN P. WEIS, OF NYACK, NEW YORK, ASSIGNOR OF ONE-HALF TO METROPOLITAN SEWING MACHINE CORPORATION, OF NYACK, NEW YORK, A CORPORATION OF DELAWARE

LUBRICATING MECHANISM FOR SEWING MACHINES.

Original application filed June 28, 1921, Serial No. 481,032. Divided and this application filed December 4, 1923. Serial No. 678,398.

To all whom it may concern:

Be it known that I, JOHN P. WEIS, a citizen of the United States, residing at Nyack, in the county of Rockland and State of New York, have invented certain new and useful Improvements in Lubricating Mechanism for Sewing Machines, of which the following is a specification.

This invention relates to lubricating mechanism for sewing machines, an object of the invention being to provide improved means for automatically lubricating various operating mechanisms of the machine whereby the machine may be rendered more compact and simplified in construction and whereby greater efficiency and effectiveness in operation may be obtained.

This application is a division of my co-pending application for sewing machines, Serial No. 481,032, filed June 28, 1921.

My invention is particularly adapted for sewing machines operable at high speeds and having mechanism for starting and stopping the machine not only at speeds between three and four thousand revolutions per minute, but also at the slowest possible speeds, the present lubricating system not only constantly and automatically lubricating the mechanism, but also providing an oil buffer or shock absorbing means for the starting and stopping mechanism.

Where, in sewing machines of the present character, the requirement of service necessitates the continual starting and stopping of the machine at varying speeds from maximum to minimum, it is essential that such operation be accomplished with the least possible shock, vibration and noise, and it is one of the purposes of the present invention to so eliminate to a large extent shocks, vibrations, and noise as to enable the machine to run smoothly and quietly at all times. It will be seen that an important advantage derived from the present lubricating system resides in the fact that it furnishes an oil cushion for absorbing the shocks or blows to which the stop clutch is subjected in operation, thus permitting the machine to be stopped and started at high and low speed without damaging the parts, and thereby increasing the efficiency of the machine and enabling it to operate effectively for comparatively longer periods of time without repair.

Other objects of this invention will appear in the following description and appended claims, reference being had to the accompanying drawings forming a part of this specification, wherein like references indicate corresponding parts in the several views, and wherein Fig. 1 is a side elevation of the machine with the end cap or cover of the looper mechanism shown in dotted lines, and the transmitter shown in operating position under the machine, but detached from the work table to more clearly illustrate the relation of the transmitter with the sewing machine; Fig. 2 is a top plan view of the transmitter shown in Fig. 1; Fig. 3 is a front perspective view of the sewing machine, transmitter and treadle connected for operating the same; Fig. 4 is a perspective view of the end cap for covering the looper and the thread controlling mechanisms; Fig. 5 is an end view of the needle bar operating mechanism, portions of the needle bar bushings, oil cup, and needle bar broken away to clearly show the construction, and a portion of the arm and crank shaft shown in broken lines; Fig. 6 is a back elevation of the machine, illustrating the connections for the needle drive and a portion of the looper and feed actuating mechanisms; Fig. 7 is a perspective view showing the inside wall of the back cover plate with the stop motion lever and its connecting parts assembled thereto; Fig. 8 is a vertical section taken through the vertical center line of the crank shaft bearing, showing the crank shaft, the assemblage of the clutch wheel with a portion of the stop motion mechanism, and the clutch hand wheel for turning the mechanism of the machine by hand, the frame of the machine being represented by broken lines; Fig. 9 is a transverse section of Fig. 12, and shows particularly the stop clutch balls in a clutched position; Fig. 10 is a view similar to Fig. 9, but shows the stop clutch balls in a non-clutching position; Fig. 11 is a detail view of the collar which forms a retainer for the clutch spring; Fig. 12 is a fragmentary perspective view of a portion of the crank shaft and stop clutch shaft; Fig. 13 is a top plan view of the feeding mechanism, the overhanging arm and cylinder of the machine being shown in broken lines; Fig. 14 is a side elevation of the feeding mechanism, parts being broken away to clearly

show the assemblage, the overhanging portion of the arm and the machine frame being indicated in broken lines; Fig. 15 is a side elevation illustrating particularly the 5 forwardly extending cylinder and the looper mechanism supported thereby; Fig. 16 is an end elevation of the cylinder and looper actuating means partly in section; Fig. 17 is a side elevation of the stop lever, the actuating 10 rod therefor, the stop clutch brake shoe and brake shoe lever being shown in full lines, and the frame in broken lines; Fig. 18 is a detail plan view of the stop lever, showing its mounting in the cover plate and 15 machine frame, the same being shown in broken lines; Fig. 19 is a fragmentary perspective view of the end of the cylinder, showing a portion of the throat plate, looper thread clamping means, and the looper 20 thread guide tubes which conduct the thread from the rear of the machine to the thread controlling mechanism; Fig. 20 is a vertical sectional view of the crank shaft and bearings thereof illustrating the manner in which 25 the parts are lubricated from the overhead reservoir and the tubular outlets leading to the several bearings, also showing in elevation the oil pump, the oil pump drive wheel, and the tubes conducting the oil from the oil 30 pump to the reservoir at the top of the machine; Fig. 21 is a side elevation of the mechanism shown in Fig. 20, illustrating the drip lip attached to the inside inclined face of the rear cover for conducting a portion 35 of the lubricant to the shock absorbing oil buffer carried by the stop lever; and Fig. 22 is a detail view of the reservoir at the top of the machine, portions being broken away to show the filter and the construction of the 40 oil gauge or indicator.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

Referring particularly to Figs. 1, 3, 5, 6, 8, 17, 20 and 21, it will be seen that the present machine is mounted on a suitable table 1 and comprises a machine frame of special 55 construction having flanges 2 and 3 for supporting and securing the machine to the table. The main portion or trunk of the frame is preferably of hollow rectangular construction, closed at the bottom and having a front wall 4, and a rear wall 5 provided with an opening 6 adapted to be closed by a cover plate 7 attached thereto in any suitable manner. This cover plate has a hollow projection 8 within which operates a 60 stop lever 118. The outline or shape of the 65

opening 6 is irregular in form and is indicated at 6^a, 6^b, 6^c, 6^d, 6^e, and 6^f, Fig. 6, the cover plate 7 being of similar form and adapted when closed to seal the opening against leakage of oil.

As shown in Figs. 17 and 21 the rear wall 5 is inclined to the left of the perpendicular, an advantage thereof being to assist in properly conducting the lubricant from one interior part to another and to finally conduct it into the reservoir formed by the bottom 9 and side walls 4, 5, 13 and 16 of the frame. To empty the reservoir I provide a drain pipe 10 tapped into the bottom 9. The front wall 4 is provided with a boss 11, bored to receive the cylinder 12. The side wall 13 is provided with a boss 14 to receive one of the crank shaft bushings 15. The opposite side wall 16 has a projecting rib 17 parallel to the wall 4, curved at 18, and provided with two bosses 19, the rib extending down the opposite side, parallel to the rear wall 5 as at 20, Fig. 17.

Located on the side wall 16 near the bottom is a boss 21, forming together with the 90 bosses 19 a suitable seat for the belt guard 22 which covers the drive belt 23, and the clutch and pump wheels 93 and 425.

The side walls 16 has a rectangular opening 24 into which projects the laterally extending portion 118^a of the stop lever, Fig. 18, this opening also affording a passage for the lubricant returning from the outer bearing 25 of the bushing 99 carried by the belt guard 22, Figs. 6 and 8. Above the opening 24 in the side wall 16 is an inwardly projecting boss 26 bored to receive bushings 101 and 101^a for supporting the crank shaft. The top portion of the frame carrying the boss 26 is indicated at 27 and the top wall 10 of the frame at 28, Fig. 20, wherein the needle driving means and oil distributing reservoir are located. Projecting inwardly from the front wall is a boss 29 also bored to receive a bushing 29^a for supporting the crank 11 shaft. Adjacent to the bottom 9 of the frame, and located in the side wall 16 is an inwardly projecting boss 30 bored to receive a pump casing 31.

Projecting from the front wall 4 is an 115 overhanging arm 32 terminating in the needle bar and presser bar bearings 33. Above these bearings is a rectangular opening 34 through which the presser spring and lifter lever operate. This overhanging arm 32 is 120 provided with suitable bearings 37 and 38 for the needle operating rock shaft 39. Secured to the forward end of the rock shaft 39 by screws 40 is a needle bar operating arm 41. The end of the shaft 39 is tapped 125 to receive a screw 42 and a thrust washer 43 thereby to prevent end movement of the arm 41 on the shaft 39. At the outer end of the arm 41 by means of a joint pin 44 is secured a link 45, the bottom end thereof being con- 130

nected by means of a joint pin 46 to an end piece 47 tapped into the needle bar 48 and clamped with a lock nut 49. The needle bar is hollow and the lower end is tapped to receive the needle holder 50 which carries the needles 51. The needle bar is provided with two openings 52, the upper one being an inlet and the lower one an outlet for oil for the purpose of internally oiling the upper and lower needle bar bushings 53 and 54.

Secured to the top of the upper bushing 54 is an oil cup 55 provided with a felt oiler, carrying sufficient lubricant for the needle bar, but preventing the oil from dripping and soiling the goods. An intermediate felt oiler 56 is provided between the two bushings. These felt oilers wipe the needle bar in its reciprocating movement, keeping it clean and properly lubricated.

To the rear end of the rock shaft 39, adjacent to the bearing 37 is secured a crank arm 57 and ball stud 58, to which is connected the upper end of a ball connection 59. The lower end 60 also has a ball socket to fit over the ball 61 of the crank shaft.

With reference particularly to Figs. 6, 8, 11, 12 and 20, the crank shaft comprises bearing portions 62 and 63, the bearing 62 being integral with the crank disk 64 and the ball 61. The crank 65 is integral with the ball 61 and the portion of the shaft 63, the crank shaft 66 is also integral with the shaft portion 63 and with a ball 67, and the crank disc 68 is integral with balls 67 and 69, the latter forming a part of the shaft portion 70, shown in section in Fig. 8. The end portion 62 of the crank shaft is provided with a series of clutch teeth 72 to co-act with other clutch teeth 73 carried by a stub shaft 74 secured

40 to a hand wheel 75 adapted for the purpose of turning the crank shaft and operating the mechanism of the machine by hand, if desired the shaft 74 is provided with a reduced neck 76 for the reception of the coiled spring 77 carried in the annular groove 78 of the bushing 15. The position of the spring with respect to the shaft neck 76 is such as to normally hold the clutch teeth 73 out of engagement with the clutch teeth 72, the con-

45 traction of the spring on the edge 79 of the neck tending to draw the shaft outward. Thus when the hand wheel 75 is forced inward by the hand of the operator to engage the clutch teeth for turning the shaft, the spring 77 is forced out of the neck and is expanded so as to cause the same to embrace the edge 79. When the inward pressure of the hand upon the wheel is removed, the contraction of the spring draws the shaft to 50 a position where the spring enters the neck 76, disengaging the clutch teeth, and thus preventing the wheel from rotating during the operation of the machine.

Referring particularly to Figs. 6, 7, 8, 11, 12, 17 and 18, it will be seen that the portion

of the shaft 70 is drilled at 80 to receive the reduced end 71 of the stop clutch shaft. A portion of the shaft extension 70 is enlarged to form the semi-circular key-way 81 which extends the entire length of the hole 80 and receives a semi-circular key 82 formed as an integral part of the reduced portion 71 of the stop clutch shaft. The telescoping of these parts provides a convenient way of connecting the parts for quick coupling and uncoupling, as it is necessary at times to withdraw the stop clutch shaft in order to renew the wedge blocks 83, hereinafter described, or other parts.

Adjacent to the end portion 70 of the crank shaft, and between the faces of the bushings 101^a and 101, is located a collar 86 provided with a hole 87, and a key-way 87^a, adapted to receive and embrace the end 71 of the stop clutch shaft for rotary movement therewith. The bushing 101 is recessed to receive the collar 86 so that the faces of the two bushings are flush with each other, thereby limiting the movement of the collar. A coil spring 87 is carried in a groove 88 terminating at 87^c on one side of the center line of the shaft hole 87^a, see Fig. 11, and on the other side terminating at 87^b. The groove has two openings 87^e and 87^f through the rear wall of the collar 86, and through these openings the end of the spring 87 may be seen when assembling the parts, as one end of the spring abuts against the end 87^c while the other end exerts pressure against a pin 89 projecting through the opening 87^e and secured to and carried by a rockable stop clutch sleeve 90.

The stop clutch sleeve 90 is bored to fit over the reduced end portion 71 of the stop clutch shaft and such bore is also provided with a semi-circular key-way to fit over the semi-circular key 82. The enlarged section 85 of the stop clutch shaft is provided with three radially disposed pockets 84 into which are loosely seated segmental wedge blocks 83 which receive wedge balls 91. The sleeve 90 is bored to fit over the enlarged portion 85 of the stop clutch shaft, and such portion is provided with three apertures, each of which carries a ball 91. The key-way of the sleeve being larger than the key permits the sleeve 90 to be rocked on the shaft by spring 87, as hereinafter described, sufficiently to cause the three balls 91 to shift from a low non-clutching position on the wedge blocks 83 as illustrated in Fig. 10 to a clutching position where the balls are projected outwardly to grip the ball race 92 carried by the clutch or driving wheel 93, as illustrated in Fig. 9.

The clutch wheel 93 is provided with a belt groove 94, and is made in two sections having respectively hubs 95 and 96. The hub 95 operates in the bearing 97 while the hub 96 operates in the bearing 98, so that

the pull of the belt on the wheel 93 is taken up by these two bearings. The bearing 97 is formed in the bushing 99, carried by the boss 100 of the belt guard 22, and also forms an end bearing for the enlarged end portion 85 of the stop clutch shaft. One end portion of the stop clutch sleeve 90 extends into the hubs 96 and 95 of the clutch wheel and the opposite end portion thereof has a bearing in the bushing 101, supported in the boss 26 of the machine frame. This bearing is also in the form of a bushing and is provided with a cut-out 102 which extends up from the bottom for the entrance of a stop finger. This cut-out registers with an eccentrically formed stop tooth 103 (see Fig. 17) formed in the clutch sleeve 90. Directly above the cut-out or opening 102 is located a brake shoe 104 which operates in an opening 105 at the top of the bushing 101 against the stop clutch sleeve 90. A spring 106 is carried between a screw collar 108 and a shoulder 109 of a presser plug 107, and exerts downward pressure thereon, the shoulder 109 resting directly on the brake shoe.

The opposed surfaces of the presser plug and brake shoe are cut out forming a space between them to receive the free end 110 of the brake lifting lever 111 adapted to rock on a stud screw 112. The free end of the brake lifting lever 111 is provided with a segmental or arcuate face 113 centered substantially at 114, Fig. 17. Co-acting with the curved surface 113 is an anti-friction roller 115, secured by a shoulder screw 116, to an upstanding arm or projecting member 117 of a stop lever 118, mounted on conical screws 119 tapped into the side wall of the projecting portion 8 for pivotally supporting the stop lever 118. A stop finger 120 is connected by a joint pin 121 to the free end of the stop lever, the upper end 122 co-acting with the stop clutch tooth 103, and the lower end 123 co-acting with the oil buffer indicated generally at 124 which is supplied with oil from a reservoir 125, formed as a part of the stop lever.

To overcome the falling weight of the free end of the stop lever 118, a spring 126 attached at one end 127 to the inside wall of the cover plate 7 is secured as at 128 to the stop lever, and normally urges the end 122 of the stop finger into engagement or co-action with the stop clutch tooth 103. From a consideration of Fig. 18 it will be seen that the stop lever 118 is provided with a rectangular opening 129, within which is pivotally secured a sleeve 130 by screws 131 and 132. The reduced end 132^a of the screw 132 is somewhat longer than the reduced end 131^a of the screw 131 so as to project through the wall of the sleeve and ride freely against the flattened face 133 of the push and pull rod 134, so that the end of the screw may engage the shoulder 135 of the flattened face

133 upon the predetermined downward travel of the rod.

The upper end 136 of the rod 134 co-acts with one end 177 of a rock lever 174, which is pivoted at 175 on the frame of the machine. The opposite end 178 of this lever overhangs and cooperates with one end 179 of a presser foot lifting lever 180 which is pivoted at 181 to the overhanging arm 32 of the machine frame. Supported in the bearing 33 is a bushing 187 within which reciprocates a presser bar 183 having a presser foot 188 secured to the lower end thereof. A further detail description of the presser foot operating mechanism is not deemed necessary herein since the same is fully described in my co-pending application.

Referring particularly to Figs. 1, 2 and 3 it will be seen that the power transmitter consists of a main bracket 143 secured to the under surface of the table 1 in any suitable manner, the bracket having an arm bored to receive a shaft 144. Upon this shaft is mounted a cone pulley 145 over which operates the belt 146 for transmitting power from any suitable line shaft to the pulley. This pulley 145 is provided with a frictional surface 147, co-acting with a similar frictional surface 148 of the driven pulley 149 also carried by the shaft 144. The belt 146 is driven by the pulley 149 for operating the sewing machine. A bracketed lever 150 is carried by the rock shaft 151 supported in the arm 152 for rocking movement, and the forwardly projecting end 153 of the lever 150 has a suitable angular or camming face adapted upon rocking the lever inwardly to exert inward pressure on the cone pulley 145 thereby to force the frictional surfaces 147 and 148 together so as to clutch the pulleys 145 and 149 for rotation.

The shaft 151 has rockably supported thereon at 154 the lever 139, provided with a stud 155 to which is connected the upper end of a rod 156. The lower end is connected by a coupling 157 to a rod 158 connected to a floor treadle 159, whereby the transmitter may be operated in order to control the speed of the machine.

A brake lever 161 is also secured to the shaft 151, and the arm 152 is provided with a lug 162 having a spring 163 interposed between it and a lug 164 carried by the brake lever 161. The latter is provided with a frictional surface 165 to engage the rim 166 of the pulley 149 in order to quickly stop the pulley each time the rod 156 is thrust upward to shut off the power. Attached to the bracket 143 is a projecting member 167 carrying a stub shaft 168 upon which rotates an idler pulley 169, which directs the upward run 170 of the belt 23 to the clutch wheel 93.

Suitable means is provided for regulating the speed of the pulley 149 and thereby regu-

lating the speed of the sewing machine. A detailed description thereof is not deemed necessary herein since the same is fully described in my co-pending application.

5 The lever 150 and the brake lever 161 are secured to the rock shaft 151 and hence a downward pressure of the rod 156 swings the brake lever 161 away from the rim 166 somewhat before the frictional surfaces are brought firmly together. A reverse action of the rod 156 of course causes the frictional surfaces to separate prior to the effective operation of the brake lever 161 against the rim 166. Thus when the treadle is pushed 10 down and the outer end of the lever 139 is shifted downwardly, the pulleys 145 and 149 will be clutched together thereby causing the transmitter to impart movement to the belt 23 in the direction of the arrows shown in 15 Fig. 1, so as to rotate the clutch wheel 93. This operation will take place prior to any actuation of the stop lever 118 by virtue of the fact that during the initial downward movement of rod 134 the screw 132^a rides in 20 the groove or flat surface 133. Upon a further downward movement of the foot treadle and the rod 156 connected therewith, the push and pull rod 134—137 will be shifted downwardly to a position where the shoulder 25 135 will strike the screw 132^a and swing the lever 118 downwardly on the pivots 119 thereby shifting the stop finger 122 out of 30 engagement with the clutch tooth 103.

Simultaneously with this movement the 35 roller 115, which is normally at rest above and out of contact with the brake lifting lever 111, is shifted into engagement with the corner 115^a of the lever, thereby swinging the lever on the stud screw 112, lifting the pressure plug 107 slightly against the 40 tension of the spring 106, and releasing the friction of the brake shoe 105 on the sleeve 90. This operation permits the spring 87 which is under tension to rock the sleeve 90 relatively to the shaft 71, thereby shifting 45 the balls 91 into a clutching position, at which time the crank shaft is caused to rotate to start the machine.

Referring to Figs. 13 and 14, a four-motion feeding mechanism co-acting with the 50 presser foot is provided for feeding the work through the machine. This mechanism comprises a feed dog 208, which may be of any preferred form to suit the character of work. 55 This feed dog is adjustably and detachably mounted upon a feed bar 213, which is rockably supported in the cylinder 12 by a swinging yoke link 220 embracing the bar. Four-motion movements are transmitted to the 60 feed bar by the ball crank 69 of the crank shaft operating in the bearing 230 of the feed lever 231. The rear end of the feed bar 213 is connected to the feed lever 231 by means of a joint pin 233. Mechanism is provided for adjusting and regulating the

length of stitch or the throw of the feed dog, preferably by means of self-locking adjusting mechanism. A detailed description of this mechanism is not deemed necessary herein, the same being fully described in my 70 co-pending application.

Referring to Figs. 15 and 16, it will be seen that the looper or thread control mechanism, which is supported by the cylinder 12, is operated from the ball crank 67 of the 75 crank shaft, the latter having connected thereto a ball joint 265 of a lever connection 266. The lower end of the lever 266 is provided with a ball socket 267 for receiving the ball 268 of an arm 269 clamped on a 80 rock shaft 270, which is supported in bearings of a yoke bracket 272 having a tapered shank 273 adjustably secured in the wall 13 of the machine frame by screws 274. A looper shaft 292 extends through the cylinder 12 and is supported at its forward end by a suitable bearing 248 secured in the cylinder 12 by screws 293, the rear end of the looper shaft being connected by suitable connections, fully described in my co-pending 85 application. It will be seen that the lever 266 is fulcrumed on the arm 269 and as a result in operation the loopers 311 and 312 which are suitably supported on the forward end of the shaft 292, are given an elliptical 90 path of movement. By loosening the screws 274 and inserting a screw driver in the slot 274^a the yoke bracket 272 may be turned so as to tilt the position of the rock shaft 270. Such adjustment of the rock shaft changes 95 the path of movement of the lever 266 about the fulcrum ball 268 thereby adjusting the elliptical path of movement of the loopers. A further detailed description of the mechanism for adjusting and operating the looper 100 mechanism is not deemed necessary herein since the same is fully described in my co-pending application.

Co-acting with the stitching and feeding mechanism is a throat plate 334, see Fig. 110 110, secured to the forward bearing 248 by screws 335, Fig. 15. The throat plate is provided with the usual feed slots 337 through which operate the serrated surfaces 336 of the feed dog 208, see Fig. 13, the throat 115 plate also being provided with the usual needle holes (not shown) through which the needles operate. The throat plate is of segmental construction forming with the cylinder 12 a complete circle when attached thereto, the cylinder being cut away on the lines 338—338 to receive the throat plate. A projecting tongue 338^a of the throat plate 120 cooperates with a groove formed in the cylinder, Fig. 15, so that the projecting portion 339 overlaps the tongue 338^a, thereby securely holding the rear end of the plate from tipping or moving when the pressure of the foot is brought to bear upon the outer overhanging end of the throat plate.

Referring particularly to Figs. 1, 3 and 4, the forwardly extending end 340 of the throat plate is provided with beveled or inclined edges 341, and an end cap or cover 343 fits thereover, the dove-tailed grooves 342 of the cap cooperating with the inclined portions 341 and hence the same may be shifted on and off the forward end of the throat plate. The side walls of the cap at 10 344 are partially slotted to make them flexible so that the cap will yield and properly fit over the beveled or inclined edges of the throat plate. The end cap is hollow to provide free working space for the loopers 15 and other parts adjacent thereto. In order to secure the cap 343 to the cylinder and prevent it from becoming disengaged from the throat plate during the operation of the machine the cap is provided with suitable 20 locking means comprising a lock spring 343^b projecting through an opening 343^a for convenient manipulation by the operator, the cap being removed by pressing inwardly on the spring to disengage the hook end 343^c 25 from a notch 343^d formed in the side wall of the cylinder 12, see Fig. 15. This lock spring is suitably secured inside of the end cap as by a screw 343^e Fig. 4.

As illustrated in Figs. 1 and 19, the cylinder 12 may be provided at its forward end with a projecting portion 345 extending outwardly to correspond in length approximately with the overhanging portion 340 of the throat plate, the extension 345 being 30 provided with an end wall 346 to prevent lubricant from escaping. The curved side walls 347 of this extension are adapted to lie in juxtaposition to the curved walls of the cap 343 thereby forming a support upon 35 which the bottom edge 348 of the end cap rests.

It will be seen that by reason of the fact that the feeding and looper mechanisms are arranged and supported within the cylinder 40 45 12, the same having the enlarged opening covered by the throat plate extending a considerable distance in the rear of the needles I may do away with the use of a cover plate, and as a result of this construction greater rigidity of the parts is secured, as well as free access to the interior of the cylinder, thus eliminating loose parts with the added advantage of using a cylinder of equal diameter throughout its length.

The cylinder is preferably constructed of steel tubing of small diameter. Small tubular work may be handled with greater facility than the usual casting which is tapered from the free end toward the machine frame, and at the same time giving the increased advantage of greater strength and rigidity. In the present machine the cylinder is detachably secured in the boss 11 50 55 by spot clamping screws 349, permitting the cylinder to be removed and replaced by dis-

connecting the operating means for the looper and feed within the rear trunk of the machine. To prevent the leakage of oil between the cylinder 12 and the boss 11 a wick insert 350 of suitable material is provided which fits into a groove of the cylinder 12 to form a leak-proof joint between the parts. 70

Referring to Figs. 1, 3 and 19, it will be seen that mechanism is provided for controlling the looper threads, this mechanism being located adjacent to the free end of the cylinder 12. A detailed description of the means for controlling the looper threads is not deemed necessary herein, since a detailed description thereof is contained in my co-pending application, it being sufficient to state that this mechanism comprises in general a thread clamp or nipper 374 and a thread take-up or controller (not shown) 75 which give and take up the thread at the desired intervals of each stitch forming cycle. This mechanism is controlled by means of a two-arm rock lever 351 pivotally supported by the end bearing 248. 80 This rock lever has an arm 353 which is provided with a cam end 355 actuated by a cam 359 on the looper shaft 292. It will be noted that this mechanism is all accessibly located in and covered by the end cap 85 of the machine, such location of the entire thread controlling mechanism, including the looper mechanism, offering important advantages in threading and adjustment. 90

The present machine is provided with an improved automatic lubricating mechanism, which comprises a suitable pump to deliver oil from the bottom reservoir to a reservoir at the top of the machine, from which the oil is conducted to each of the bearings through tubular conduits, or otherwise. This lubricating means supplies oil for the oil buffer and provides a shock absorbing fluid to and between the surfaces of parts subject to shock in the starting and stopping, as well as shocks caused by the rapid reciprocation and rotary movements of other parts. It also obviates the necessity of oiling the machine several times each day, as practically all of the parts requiring constant lubrication are located inside the machine frame, thus preventing any of the flying oil escaping to the outside of the machine where it would be injurious to the goods, and objectionable to the operator. 100 105 110 115 120 The lubricating system employed is an improvement in part over that shown and described in my Patent No. 1,348,527, of August 3, 1920, certain other changes and modifications being made to adapt it to the present machine. In the patent referred to, I employed a top and bottom hollow arm, a needle drive shaft rotating in a tube, and a looper shaft operating in a tube, each of 125 130 135 the shafts being of tubular construction and

the lubricant being conducted through the hollow shafts. In the present improvement however the overhanging arm of the machine is of L-shape construction and the needle driving means has a rock shaft instead of a rotary shaft. The needle bar is operated through an oscillating arm 41 carried by the shaft, and as a result of this construction the frame structure is considerably reduced in size due for instance to the elimination of the usual gearing and crank mechanism for reciprocating the needle bar. A simple means is also provided for lubricating the needle bar, which means is independent of the lubricating means for the major parts of the machine. The looper and feeding mechanisms operating within the cylinder are automatically lubricated, as well as the other parts within the machine frame. Thus the only parts which need to be lubricated with the hand oil can are the needle bar, needle bar driving link or arm, and the forward bearing of the rock shaft. All the other active parts being encased are automatically lubricated.

In the patent above referred to a detachable reservoir and filter for the lubricant was used, the same being placed underneath the trunk opening of the machine frame. In the present construction the frame itself forms a reservoir having the four sides and the bottom integral, and when the rear cover plate is applied, the entire structure is enclosed and is sealed against leakage. In the present improvement the lubricating system comprises a pump belt wheel 425 carried by the shaft 426. At the end of this shaft is attached a small gear 427 which is in mesh with and drives a similar gear 428 carried by a shaft 429. These gears operate in a suitable recess of the pump casing 31 secured in the boss 30 by a set screw 430. The pump casing is provided with a peripheral groove filled with wicking 431 for making a leak-proof fit between the casting and the hole into which it fits. The gears are covered by a circular plate 432 secured to the pump casing 31 by screws 433, a packing plate 434 being interposed between the plate 432 and the pump casing to make it airtight.

The plate 432 is provided with an inlet for the lubricant which is drawn in by the gears and forced up by the tube 435 which has an angular bend 436 and a vertical portion 437. This tube is secured at 438 in the bottom wall of the reservoir 439. The upper end 440 of the tube projects through the bottom 441 of a filter made of very fine wire mesh screen, the filter having the side walls bent up, as indicated at 442 to fit snugly within the walls of the reservoir 439. The oil forced up by the pump through the tube 437 and out of the end 440 lifts the oil gauge plunger to the dotted line po-

sition 444 of Fig. 22, the oil striking the collar 445 and lifting the gauge as shown. The depending stem 446 of the gauge is provided with one or more flutes to permit the passage of oil into the reservoir between the stem and the inside walls of the tube 438. Thus the gauge indicates to the operator the flow of oil, as each time the machine is started the gauge is lifted to the dotted line position, irrespective of the speed at which the machine is operated. When there is not sufficient oil in the reservoir to supply all the parts of the machine, air is admitted in the opening of the circular plate 432, through which the oil enters, and such air will escape from the end 440 of the tube without lifting the gauge 443 above the top cover plate 447, which covers the opening through which the reservoir is inserted into the top frame portion of the machine. The cover plate is held in place by a shoulder screw 448 on one corner and a thumb screw 449 at the other corner, and may be swung laterally on the screw 448 by loosening the screw 449 and swinging the cover to one side for removal of the reservoir or filter. The gauge 443 operates through a hole in the cover plate as shown by the sectional view, Fig. 22. The filtering screen 441 is of suitable depth to contain a quantity of oil and is at the same time so located as to permit a space 450 for lubricant to be distributed to the various tubular outlets, or parts indicated at 451, 452, 453, and 454, each of which having its delivery end so located as to deliver oil therefrom to the respective bearings. The bottom wall of the reservoir is also provided with one or more holes (not shown), through which the oil may escape to lubricate other bearings, which can be reached without the aid of depending tubes. The tube 454 leads oil to the funnel 455 carried by the horizontal tube 456, the end 457 directing lubricant to the bushing 15, and the opposite end 458 directing lubricant to the bushing 101. The oil escapes from holes in the bottom of the reservoir to supply the needle rock shaft connection 59 and the rear bearing 37.

The tube 451 supplies the intermediate bearings of the crank shaft 63. The tube 452 supplies the crank 67, the looper actuating mechanism, and the mechanism below it. The tube 453 supplies the crank 69 and the feeding mechanism with lubricant. A portion of the lubricant thrown from the cranks 67 and 69 is caught by the pocket 118^b and oils the pivots 119, see Fig. 18. Other portions are caught upon the plate 459 secured to the cover plate 7 by screws 460, and which has a tapered extension which terminates in a spout end 461 for delivering lubricant directly to the reservoir 125 of the stop lever 118, which supplies the oil buffer 124 of the stop lever, see Figs. 7 and 20.

The oil buffer 124 is connected with the reservoir 125 by holes 124^a leading from the chamber of one to the other for the passage of oil.

- 5 The bushing 15 is supplied with lubricant from the end 457 of the horizontal tube 456 and has a recess 462 to receive the lubricant. Thence it flows down through the hole 463 directly on the shaft 62. The lubricant escapes from around the shaft through the annular groove 78, returns through the horizontal outlet 464, and escapes at 465 into the interior of the machine, see Figs. 8 and 20. The oil delivered from the outlet 15 458 into the hole 466 of the bushing 101^a is led directly to the end portion of the shaft 70, which is drilled at 466^a to conduct the lubricant to a central bore 467 extending thru the hollow stop clutch shaft 71, see Fig. 20 8. The lubricant escapes at 468 to lubricate the bearing 25 of the shaft in the bushing 99, and the escaping lubricant is caught in a receptacle 469, and thence passes through the tubular outlet 470 into the interior of 25 the machine.

Some of the oil which escapes to the belt wheel 93 is thrown off by the flanges 471 and is caught inside the belt wheel guard 22 by the hollow receptacle. Another portion 20 which may be thrown off by the wheel or the belt is caught in the lower hollow projection 472, having a tubular outlet 473 leading to the interior of the machine. The tubular outlets 470 and 473 projecting from the receptacles 459 and 472 deliver the lubricant caught thereby through the rectangular opening 24 in the side wall of the machine frame. Other portions of the lubricant that escape from the opposite side of the wheel 35 are caught by the inner wall of the projecting rib 17 and also conducted to the interior of the machine. The upper edge of the rectangular opening 24, as indicated at 474, Fig. 21 is beveled from the outside to the inside so that the drippings of oil will fall to the interior of the frame. The drive belt 23, the downward run of which operates the pump wheel 425 is also located inside of the belt wheel guard 22.

45 When the belt 23 is put in operation by the transmitter, the pump will supply the reservoir at the top of the machine, the pump being operated independently of the driven mechanism of the machine, the operation of the same depending upon the operation of the treadle by the operator. This is an important advantage because the machine is sure to be lubricated before it is operated, thus minimizing the liability of the 50 machine being operated with any of the bearings dry.

In order to conduct the lubricant into the cylinder 12 for lubricating the parts contained therein, the feed bar is made trough-shaped at 475 and 476, see Fig. 13, so that

the lubricant will flow down the inclined surface 477 of the feed bar 213, see Fig. 14, into the troughs 475 and 476. These are connected by a channel 478 having an opening at 479 to lubricate the bushing 225 which 70 supports the feed bar. A part of the lubricant flows down the link 220 to lubricate its bearing on the stud screw 219, and portions flow out through the opening 480, Fig. 14, passing through the side walls of the bearing 248, which guides the forward end of the feed bar. The portion 481 between the looper shaft bearing and the slot for the feed bar is provided with a hole or slot for the passage of lubricant into the looper shaft bearing. A portion of the lubricant escapes along the looper shaft onto the cam 359 and lubricates the frictional surfaces of the parts of the thread controlling mechanism located within the end cap of the machine. A portion of the lubricant is caught in the extension of the cylinder and prevented from escape by the end wall 346, Fig. 19. A return passage 482 is provided in the end bearing 248 to permit the lubricant to

return from the inside of the cylinder to the interior of the machine by passing through a slot 405, Fig. 16, through which the thread tubes 404 pass. In order to accomplish the return of the lubricant from the mechanisms at the front end of the cylinder, the machine is mounted on the table at a slight angle, the free end of the cylinder 12 being slightly higher than the inner end so that the lubricant will flow to the interior of the machine. 95

From the foregoing it will be noted that the machine frame within which is housed the drive shaft and operating parts for the feed and thread control mechanism forms of itself a reservoir having the four sides and bottom integral, and when the rear cover plate 7 and the belt guard or housing 22 are applied the entire frame structure is closed and is sealed against any leakage of oil. 100

The cylinder or work arm which houses the feed and thread control mechanism is also constructed so as to be oil-tight, and provision is made for automatically lubricating all bearing surfaces within the cylinder. The inclined trough-shaped feed bar enables a continuous flow of oil to be conducted into the cylinder and by means of oil holes leading to different bearings and also by virtue of the movement of the feed bar which throws the oil to adjoining parts, all frictional surfaces in the cylinder are constantly lubricated and without any oil escaping to the outside. This construction does away with the necessity of oiling the bearings from the outside of the work support, which frequently results in soiling the goods. Provision is made for conducting the oil from the cylinder back to the machine frame within which is located the 115 120 125 130

pump mechanism. It will be noted that the pump is normally submerged in oil within the frame, and therefore requires no priming, and will start to pump oil immediately upon starting the machine.

5 The gauge 444 indicates the flow of oil, and if at any time the oil in the frame or reservoir goes below the pump, thus admitting air, the gauge will not rise in the oil 10 tube or conduit. This gauge is not a pressure gauge, but is controlled by the flow of oil only, and therefore indicates whether oil is flowing when the machine is operated.

15 Although, in the present improvement, a rotary pump is preferably used, any form of pump may be used for the purpose. Also the pump may be operated otherwise than from the drive belt of the sewing machine, as for instance a reciprocating pump may be 20 operated from some part of the interior mechanisms, or from the push and pull rod 134, but the present rotary mechanism controlled independent of the machine is preferred on account of its great simplicity, 25 and reliability. The power required to operate the pump is negligible since the gears are of such tiny proportions, being preferably $\frac{5}{16}$ inch in diameter and $\frac{3}{2}$ inch thick, and at the same time they produce an ample 30 supply of lubricant at any speed to meet the requirements.

35 It is to be understood that by describing in detail herein any particular form, structure or arrangement, it is not intended to limit the invention beyond the terms of the several claims or the requirements of the prior art.

40 Having thus explained the nature of my said invention and described a way of constructing and using the same, although without attempting to set forth all of the forms in which it may be made, or all of the modes of its use, I claim:

1. In a sewing machine, the combination of 45 a supporting trunk having at the top thereof a forwardly extending overhanging arm and adjacent to the bottom thereof a forwardly extending hollow work arm, a shaft carried by each of said arms, a main drive shaft located in the trunk in a horizontal plane and spaced to the side of both of said shafts, said trunk forming a single chamber for carrying oil and enclosed against leakage, an oil reservoir above said main drive 50 shaft, a plurality of conduits for supplying oil from the reservoir to different parts of the main drive shaft, a pump extending into said trunk adjacent to the bottom thereof, a conduit from said pump to said reservoir, and means for operating the pump.

60 2. In a sewing machine, the combination of a supporting trunk having at the top thereof a forwardly extending overhanging arm and adjacent to the bottom thereof a

forwardly extending hollow work arm, a shaft carried by said overhanging arm, a looper shaft carried by said work arm, a crank shaft located in the trunk in a horizontal plane and spaced below one and above the other of said shafts, said trunk forming a single oil chamber and enclosed against leakage, an oil reservoir above said crank shaft, a plurality of conduits for supplying oil from the reservoir to different parts of the crank shaft, a pump extending into said trunk adjacent to the bottom thereof, a conduit from said pump to said reservoir, and means for operating the pump.

3. In a sewing machine, the combination of a supporting trunk having at the top thereof a forwardly extending overhanging arm and adjacent to the bottom thereof a forwardly extending hollow work arm, a shaft carried by each of said arms, a crank shaft located in the trunk in a horizontal plane and spaced to the side of both of said shafts, feeding means carried by said work arm, feed actuating mechanism connected with said crank shaft, said trunk forming a single oil chamber and enclosed against leakage, an oil reservoir above said crank shaft, a plurality of conduits for supplying oil from the reservoir to different parts of the crank shaft, a pump extending into said trunk adjacent to the bottom thereof, a conduit from said pump to said reservoir, and means for operating the pump.

4. In a sewing machine, the combination of a supporting trunk having at the top thereof a forwardly extending overhanging arm and adjacent to the bottom thereof a forwardly extending hollow work arm, a shaft carried by each of said arms, a main drive shaft located in the trunk in a horizontal plane and spaced to the side of both of said shafts, said trunk forming an oil chamber and enclosed against leakage, an oil reservoir above said main drive shaft, a plurality of conduits for supplying oil from the reservoir to different parts of the main drive shaft, a pump extending into said trunk adjacent to the bottom thereof, a conduit from said pump to said reservoir, and means for operating the pump.

5. In a sewing machine, the combination of a supporting trunk having at the top thereof a forwardly extending overhanging arm and adjacent to the bottom thereof a forwardly extending hollow work arm, a shaft carried by each of said arms, a crank shaft located in the trunk in a horizontal plane and spaced to the side of both of said shafts, said trunk forming an oil chamber and enclosed against leakage, an oil reservoir above said crank shaft, a plurality of conduits for supplying oil from the reservoir to different parts of the crank shaft, a pump extending into said trunk adjacent to

the bottom thereof, a conduit from said pump to said reservoir, and means for operating the pump.

6. In a sewing machine, the combination 5 of a machine frame having an oil reservoir, a drive shaft, means for operating the same, a hollow work support extending from said machine frame, feeding and looper mechanism located in said work support, and 10 means for lubricating said feeding and looper mechanism and including a trough-shaped feed bar for conducting oil into the work support.

7. In a sewing machine, the combination 15 of a supporting trunk having at the top thereof a forwardly extending overhanging arm and adjacent to the bottom thereof a forwardly extending hollow work arm, a shaft carried by each of said arms, a crank 20 shaft located in the trunk between and extending transversely to and connected with said shafts, said trunk forming an oil chamber and enclosed against leakage, an oil reservoir above said crank shaft, a plurality 25 of conduits for supplying oil from the reservoir to different parts of the crank shaft, a pump extending into said trunk adjacent to the bottom thereof, a conduit from 30 said pump to said reservoir, and means for operating the pump.

8. In a sewing machine, the combination of a supporting trunk having at the top thereof a forwardly extending overhanging arm and adjacent to the bottom thereof a 35 forwardly extending hollow work arm, a shaft carried by each of said arms, a crank shaft located in the trunk between and extending transversely to and connected with said shafts, said trunk forming an oil chamber and enclosed against leakage, an oil 40 reservoir above said crank shaft, a plurality of conduits for supplying oil from the reservoir to different parts of the crank shaft, a pump extending into said trunk adjacent to the bottom thereof, a conduit from 45 said pump to said reservoir, means for operating the pump, feeding means carried by said work arm, and actuating means therefor connected with said crank shaft and including 50 a feed bar carried by said hollow work arm and constructed to convey lubricant toward the free end of said work arm.

9. In a sewing machine, the combination 55 of a supporting trunk having at the top thereof a forwardly extending overhanging arm and adjacent to the bottom thereof a forwardly extending hollow work arm, a shaft carried by said overhanging arm, a looper shaft and a feed bar carried by said 60 hollow arm, a crank shaft located in the trunk between and connected with said shafts and also connected with said feed bar, said trunk forming an oil chamber and enclosed against leakage, an oil reservoir 65 above said crank shaft, a plurality of con-

duits for supplying oil from the reservoir to different parts of the crank shaft, a pump extending into said trunk adjacent to the bottom thereof, a conduit from said pump to said reservoir, and means for operating 70 the pump, said feed bar constructed to convey oil to the forward end of the work arm.

10. In a sewing machine, the combination 75 of a hollow machine frame carrying a supply of oil and having enclosing side and bottom walls, a drive shaft in the frame and extending thru one of the side walls, a driving wheel connected to said shaft exteriorly of said side wall, a driving connection for said wheel, said side wall having an opening 80 therein, a housing member enclosing said wheel and connection and covering said opening, and means carried by said housing member for conducting oil into the frame.

11. In a sewing machine, the combination 85 of a supporting trunk having at the top thereof a forwardly extending overhanging arm and adjacent to the bottom thereof a forwardly extending hollow work arm, a shaft carried by said overhanging arm, a 90 looper shaft and feed bar carried by said work arm, a crank shaft located in the trunk in a horizontal plane and spaced from said shafts, and automatic lubricating means within said trunk for conveying oil to the 95 moving parts of the machine.

12. In a sewing machine, the combination 100 of a supporting trunk having at the top thereof a forwardly extending overhanging arm and adjacent to the bottom thereof a forwardly extending hollow work arm, a shaft carried by said overhanging arm, a looper shaft and feed bar carried by said work arm, a crank shaft located in the trunk in a horizontal plane between and 105 spaced from said shafts, automatic lubricating means within said trunk for conveying oil to the moving parts of the machine, said automatic lubricating means comprising a main oil chamber carried by the trunk, 110 a reservoir located above said crank shaft, and an oil pump extending into said trunk and having an exterior driving connection.

13. In a sewing machine, the combination 115 of a hollow machine frame comprising top, bottom and side walls forming a single chamber carrying an oil bath entirely enclosed within the chamber, a drive shaft in said chamber, a driving wheel connected with one end of the shaft, and located exteriorly of a side wall of the frame, a drive connection for said wheel, a housing member enclosing said wheel and driving connection and carried by said wall exteriorly thereof, means for conducting oil from the 120 chamber to said shaft, and means carried by said housing member for collecting oil exteriorly of said side wall and conducting the oil into said chamber.

14. In a sewing machine, the combination 125

of a hollow upright machine frame having at the top thereof forwardly extending overhanging arm and adjacent to the bottom thereof a forwardly extending work support, said frame comprising top, bottom and side walls forming a single oil chamber carrying a supply of oil entirely enclosed within said chamber, a drive shaft in said chamber and extending at right angles to said work support, said shaft having bearings in a pair of opposite side walls of said frame, a shaft detachably connected in alignment with said drive shaft and having a driving wheel located exteriorly of a side wall of the chamber, driving means for said wheel, a housing member enclosing said wheel and driving means, a detachable bearing carried by said housing member for said detachable shaft, and means for conducting 20 lubricant to said bearing.

15. In a sewing machine, the combination of a hollow upright machine frame having at the top thereof a forwardly extending overhanging arm and adjacent to the bottom thereof a forwardly extending work support, said frame comprising top, bottom and side walls forming a single oil chamber carrying a supply of oil entirely enclosed within said chamber, a drive shaft 30 in said chamber and extending at right angles to said work support, said shaft having bearings in a pair of opposite side walls of said frame, an oil reservoir located above said shaft, a pump extending into said oil chamber, and having a driving wheel located exteriorly of the chamber, a driving wheel connected to said shaft and located exteriorly of the chamber, a housing member enclosing said wheels, a conduit for 35 conducting oil from said pump to said reservoir, conduits for conducting oil from the reservoir to said shaft bearings, and means carried by said housing member for collecting oil outside said chamber, and for conducting the oil into the chamber.

16. In a sewing machine, the combination of a frame having an oil chamber and above it an oil reservoir, an oil feed pipe connected to said chamber and opening into said reservoir, means for forcing oil through said pipe from the chamber to the reservoir, and an indicating plunger extending above and below the reservoir and into said pipe and having a collar intermediate its length 55 and located exteriorly of said pipe and within the reservoir and extending over the upper end of said feed pipe for closing it, that part of the plunger extending into the pipe having means below said collar for permitting the oil to directly engage the collar at the upper end of the pipe during the flowing of the oil, the movement of the plunger being controlled by the direct contact of the oil with said collar at the top 60 of the pipe.

17. In a sewing machine, the combination of a frame having an oil chamber and above it an oil reservoir, an oil feed pipe connected to said chamber and opening into said reservoir, means for forcing oil through said pipe from the chamber into the reservoir, and an indicating plunger having a part 70 slidable in said pipe and having thereabove a collar located exteriorly of the pipe and extending over the upper end of the pipe for closing it, said slidable part having means for permitting the oil to engage the collar at the upper end of the pipe during the flowing of the oil, the movement of the plunger being controlled by the direct contact of the oil with said collar at the top 75 of the pipe.

18. In a sewing machine, the combination of a frame having an oil chamber and above it an oil reservoir, an oil feed pipe connected 80 to said chamber and opening into said reservoir, means for forcing oil through said pipe from the chamber to the reservoir, and an indicating plunger having a stem slidable within said pipe and provided with flutes 85 for the passage of oil by the stem and having at the top of said flutes a collar located exteriorly of and extending over the upper end of the pipe for closing it, the movement of said plunger being controlled by the direct contact of the oil with said collar at the top 90 of the pipe.

19. In a sewing machine, the combination of a frame having a forwardly extending tubular work arm, feed mechanism located adjacent to the outer end of said arm and including a feed bar extending through said work arm, said feed bar having a lengthwise extending channel for conducting oil from its rear end to the forward end of said arm and also having an opening intermediate its ends for supplying oil at an intermediate part of said arm.

20. In a sewing machine, the combination of a frame having a forwardly extending tubular work arm, feeding and thread control mechanisms located adjacent to the outer end of said arm, and means for lubricating said mechanisms and comprising an operating member for one of said mechanisms and having a lengthwise extending channel at its upper side having an upwardly inclined part at its rear end for conducting oil from one end toward the other of said arm.

21. In a sewing machine, the combination of a frame having a forwardly extending work arm, feeding and thread control mechanisms located adjacent to the outer end of said arm, and means for supplying oil to said mechanisms and comprising a feed bar located in said tubular work arm and having a lengthwise extending channel for conducting oil from one end toward the other 125 of the tubular arm.

22. In a sewing machine, the combination of a frame, a rotatable shaft, means for stopping and starting said shaft, a power transmitter for driving said shaft, an oil reservoir, means operated by said transmitter for supplying oil to said reservoir, feeding mechanism, thread control mechanism, a pair of means connected to said shaft for operating said feeding and thread control mechanisms, one of said last means having an exterior lengthwise extending channel for conducting oil from said reservoir to said mechanism.

23. In a sewing machine, the combination of a frame having a forwardly extending hollow oil-tight work support, looper mechanism, a bearing member therefor adjacent to the front end of said work support, means for conducting a flow of lubricant thru said work support beyond said bearing, means for conducting the lubricant out of said work support, and means in front of said bearing member for preventing the escape of oil from said work support.

24. In a sewing machine, the combination of a frame having a forwardly extending tubular work arm, a feed bar projecting through said tubular work arm, means in said frame for operating said bar, said feed bar having a lengthwise extending trough with its inner end in position to receive oil from within said frame for conducting lubricant from such inner end to convey the same from one end toward the other end of said work arm.

25. In a sewing machine, the combination of a frame, a forwardly extending tubular work arm, feed mechanism carried by said arm at its free end and including a feed bar, said feed bar constructed to receive lubricant at the inner end thereof within the frame and convey the same through said tubular work arm.

26. In a sewing machine, the combination of a frame having a forwardly extending hollow work support, feeding and looper mechanisms supported thereby, a bearing located in said work support at the front end thereof, means for conducting a lubricant to said bearing, and an end cap for said work support, said work support having a bottom extension beyond said bearing forming a combined lubricant receiving means and a means for supporting said end cap.

27. The combination of a machine frame having an overhanging arm, a needle drive shaft carried by said arm, a crank shaft carried by said frame at right angles to said needle shaft, an oil reservoir above said shaft, a shaft detachably connected to said crank shaft and extending in alinement therewith, a detachable end bearing therefor, and means for conducting lubricant from said reservoir to said bearing.

28. The combination of a hollow machine

frame having an oil reservoir, a forwardly extending hollow work support having oil-tight enclosing walls, feed and looper mechanism having front and rear bearings within said work support, and means for automatically lubricating said bearings and including a feed bar for conducting the oil into and lengthwise of the work support.

29. In a sewing machine the combination of a machine frame, a crank shaft carried thereby, means for supplying lubricating oil to said shaft, stop clutch mechanism for said shaft and having an oil buffer, said machine frame having a wall thereof inclined toward said shaft, and means secured to said inclined wall for delivering oil from said shaft to said oil buffer.

30. In a sewing machine, the combination of a supporting trunk having at the top thereof a forwardly extending overhanging arm and adjacent to the bottom thereof a forwardly extending hollow work arm, a shaft carried by each of said arms, a separable two-part drive shaft located in the trunk between and extending transversely to and connected with said shafts, bearings for supporting said drive shaft, and means for automatically lubricating various parts of said drive shaft.

31. In a sewing machine, the combination of a supporting trunk having at the top thereof a forwardly extending overhanging arm and adjacent to the bottom thereof a forwardly extending hollow work arm, a shaft carried by each of said arms, a separable two-part drive shaft located in the trunk between and extending transversely to and connected with said shafts, bearings for supporting said drive shaft, and means for conveying oil to both the exterior and interior of said drive shaft.

32. In a sewing machine, the combination of a supporting trunk having at the top thereof a forwardly extending overhanging arm and adjacent to the bottom thereof a forwardly extending hollow work arm, a shaft carried by each of said arms, a separable two-part drive shaft located in the trunk between and extending transversely to and connected with said shafts, bearings for supporting said drive shaft, means for automatically lubricating various parts of said drive shaft and comprising an oil reservoir located above said drive shaft, means for conducting the oil therefrom to said drive shaft, and means for supplying oil to said reservoir.

33. In a sewing machine, the combination of a supporting trunk having at the top thereof a forwardly extending overhanging arm and adjacent to the bottom thereof a forwardly extending hollow work arm, a shaft carried by each of said arms, a crank shaft located in the trunk between and extending transversely to and connected with

said shafts, bearings for supporting said crank shaft, and means for automatically lubricating various parts of said crank shaft.

- 5 34. In a sewing machine, the combination of a supporting trunk having at the top thereof a forwardly extending overhanging arm and adjacent to the bottom thereof a forwardly extending hollow work arm, a
10 shaft carried by each of said arms, a crank shaft located in the trunk between and ex-

tending transversely to and connected with said shafts, bearings for supporting said crank shaft, means for lubricating various parts of said crank shaft and comprising an oil reservoir located above said crank shaft, means for conducting the oil therefrom to said crank shaft, and means for supplying oil to said reservoir.

Signed at Nyack, New York, this 23rd 20
day of November, 1923.

JOHN P. WEIS.
